PUNCHING MECHANISM

Paul H. Nast, Claremont, N. H., assignor to Sullivan Machinery Company, a corporation of Massachusetts

Application December 3, 1934, Serial No. 755,730

14 Claims. (Cl. 76—5)

This invention relates to punching mechanism, and more particularly to improvements in a punching mechanism for reforming the bore of a hollow rock drill steel or similar tubular articles.

5 In hollow rock drill steels, and similar tubular articles, the bore in the steel adjacent the bit and shank becomes deformed during the sharpening process, and it is often necessary to reform the bore after the sharpening process is completed. 10 This reforming operation is usually accomplished by driving a punch pin with a hammering action into the steel bore to open and reform the bore. Frequently during this reforming operation, the punch pin sticks in the steel bore and some difficulty is encountered in effecting release of the punch pin from the steel.

A primary object of the present invention is to provide an improved drill steel punching mechanism whereby the punch pin may be driven with a hammering action into and out of the steel bore, thereby to facilitate the bore reforming process. Another object is to provide an improved drill steel punching mechanism having an improved hammer mechanism for driving the punch pin into and out of the drill steel bore. Yet another object is to provide an improved hammer mechanism for percussively actuating the punch pin both during the hole opening and withdrawal operations, the hammer motor percussively actuating the punch pin during withdrawal, thereby to eliminate any possibility of a stuck pin. Still another object is to provide in a punching mechanism of the above character improved means for feeding the punching mechanism toward and from the work and having embodied therein improved feed control means. Yet another object is to provide an improved feed control means for automatically reversing the direction of feed upon completion of the hole opening function and having associated therewith improved means for varying the range of feeding movement. These and other objects and advantages of the invention will, however, hereinafter more fully appear.

45 In the accompanying drawings there is shown, for purposes of illustration, one form which the invention may assume in practice.

In these drawings,—

Fig. 1 is a plain view of the illustrative embodiment of the improved punching mechanism, together with its associated supporting means.

50 Fig. 2 is a side elevational view of the punching mechanism shown in Fig. 1.

Fig. 3 is an end elevational view of the punching mechanism shown in Fig. 1.

Fig. 4 is a vertical sectional view taken substantially on line 4—4 of Fig. 1.

Fig. 5 is a cross sectional view taken substantially on line 5—5 of Fig. 2.

Fig. 6 is a detail sectional view taken on line 6—6 of Fig. 2.

Fig. 7 is an enlarged vertical sectional view similar to Fig. 4 showing parts in a different position.

Fig. 8 is a horizontal sectional view taken substantially on line 8—8 of Fig. 5.

Fig. 9 is a cross sectional view taken substantially on line 9—9 of Fig. 7.

Fig. 10 is a vertical sectional view taken substantially on line 10—10 of Fig. 5.

Fig. 11 is a horizontal sectional view taken substantially on line 11—11 of Fig. 5.

Fig. 12 is an elevation of the control valve.

In this illustrative embodiment of the invention, there is shown a punching mechanism, generally designated 1, mounted on a suitable support 2 in juxtaposition with a suitable clamping mechanism, generally designated 3, this support and clamping mechanism being generally the same as that described in my copending application Serial No. 755,729, filed of even date herewith. Supported between the jaws of the clamping mechanism 3 is a hollow rock drill steel 4 having its bit 5 engaging a suitable stop and positioning plate 6, the clamp mechanism and stop plate maintaining the drill steel in longitudinal alignment with the punching mechanism so that the punching mechanism may be fed with respect to the drill steel to effect reforming of the drill steel bore upon completion of the steel sharpening process. As the particular form of clamping mechanism and stop plate for maintaining the drill steel in bore reforming position do not specifically enter into this invention, and are clearly described in my copending application mentioned above, further description of the same herein is considered unnecessary.

Now referring to the improved punching mechanism 1, it will be noted that secured to a vertical plane face 7 of the support 2, as by screws 45 8, is a frame 9 having parallel horizontal guideways 10, 10 and supporting improved control means, generally designated 11. Mounted in the frame guideways 10 are lateral guides 12, 12 formed on projections depending from the bottom of the cylinder 13 of a punch pin hammering mechanism, generally designated 14. This hammering mechanism is of the differential piston, valveless type, and the hammer motor cylinder 13 has a large bore 15 and an aligned re- 55

duced bore 16; and reciprocable in the bores of this cylinder is a hammer piston 17 having a large head 18 fitting the bore 15 and a reduced head 19 fitting the bore 16 and formed on a rearward projection integral with the piston head 18. A punch pin 20 is secured by a suitable pin lock 21 to a cylindrical striking block 22 reciprocably mounted in a bore formed in the front motor head 23. The rear end of the motor cylinder 10 is closed by a rear head block 24, and the front and rear heads are maintained in assembled relation with respect to the cylinder by usual side bolts 25, 25. The cylindrical striking block 22 has secured within the bore thereof, by a cross pin 26, the forward end portion of a cylindrical striking rod or bar member 27 extending axially through the bore 28 in the hammer piston and having at its rear end an integral striking head 29. During forward feeding of the punching mechanism, the hammer piston of the hammering mechanism is adapted to deliver impact blows to the rear annular striking surface of the striking block 22 to drive the punch pin 20 into the drill steel bore, and, upon reversal of the hammering mechanism during punch pin withdrawal, to deliver impact blows to the forward annular striking surface of the striking head 29 to hammer the punch pin out of the steel bore. Formed in the frame 9 with its axis lying in a vertical plane including the hammer motor axis, and located below the guideways on which the hammering mechanism is guided, is a feed cylinder whose bore 31 contains a reciprocatory feed piston 32 having its feed piston rod 33 projecting through the packed rear head of the feed cylinder and secured at 34 to a depending portion 35 of the rear head block 24. The forward end of the feed cylinder bore is closed by a threaded plug 36, and formed in the frame 9 transversely beneath the feed cylinder bore, substantially midway between the ends of the latter, is a valve bore 37 having mounted therein a rotary control valve 38. Secured to the valve rod of this valve is an operating lever 39 to which are pivotally connected at 40 parallel links 41, in turn pivotally connected at 42 to a longitudinally slideable operating rod 43. This operating rod is guided within guiding brackets 44, 44 secured to the frame 9, and is formed at its forward end with a grasping handle 45. The rotary control valve 38 is provided with an internal chamber 47 which communicates with a pressure chamber 48 formed within the frame 9, in turn communicating with any suitable pressure fluid source. The valve chamber 47 is communicable through a radial valve port 49 with a passage 50 which is connected by a port 51 to a longitudinal passage 52 formed in the frame 9, in turn connected by a conduit 53 with a chamber 54 formed in the rear head block projection 35. The chamber 54 is connected by a passage 55 to an annular chamber 56 formed in the rear head block 24 of the hammer motor. Also communicable with the valve chamber 47 through radial ports formed in the valve body are reverse and forward feed passages 57 and 58, the former communicating through a passage 59 with the forward end of the feed cylinder bore, and the latter communicating through a port 60 with the rear end of the feed cylinder bore.

The fluid distribution means for effecting reciprocation of the hammer piston of the hammering mechanism is of a well known design and comprises recesses 62 and 63 formed annularly in the walls of the reduced bore 16 of the hammer

motor and communicating through a longitudinal supply passage 64 with the pressure fluid supply chamber 56. Parallel passages 65, 65 communicate through radial ports with the reduced bore 16 at points substantially midway between the annular recesses 62 and 63 and through ports 66 with the forward end of the enlarged cylinder bore 15. The enlarged cylinder bore 15 is provided with a free exhaust passage 67 controlled by the hammer piston. When the control valve 10 is turned into a position to supply pressure fluid to the port 49, passage 50, port 51, longitudinal passage 52, conduit 53, chamber 54 and passage 55, to the pressure chamber 56, pressure fluid may flow through passage 64 and annular recesses 62 and 63, pressure fluid flowing from the former past the reduced exterior of the hammer piston projection to the rear end of the large bore 15 to act on the rear pressure area of the large piston head 18, and through the latter recess, after the piston has moved forwardly, to the rear end of the reduced bore 16 to supplement the pressure coming from the chamber 56 axially of the cylinder and which, though during hammering is somewhat throttled by the head 29, acts constantly on the rear pressure area of the small piston head 19. At this time the forward end of the cylinder bore 15 is connected to exhaust through exhaust port 67, and the pressure acting on the rear pressure areas of the hammer piston drives the latter forwardly in its cylinder. Cut-off to the larger rear area occurs when the head 19 overruns the groove 62. When the exhaust port 67 is uncovered by the rear edge of the large piston head 18, the rear end of the bore 15 is connected to exhaust, while the rear edge of the small piston head 19 overruns the radial ports of the supply passages 65, 65, thereby admitting pressure fluid from the recess 63 through these passages and ports 66 to the forward end of the large cylinder bore 15, the pressure fluid acting on the large front pressure area of the piston to drive the latter rearwardly in its cylinder against the opposing constant pressure acting on the rear pressure area of the small piston head 19. These operations are rapidly repeated during normal operation of the hammer motor, thereby effecting a rapid hammering action which is transmitted through the cylindrical punch pin block and bar to the punch pin or to the head 29, depending upon whether hammering in or hammering out is in progress. By adjusting the control valve 38, pressure may be supplied either to one end or the other of the feed cylinder, thereby to effect feeding of the punching mechanism either forwardly to drive percussively the punch pin into the drill steel bore, or rearwardly to effect percussive withdrawal of the punch pin from the steel bore.

The improved means for effecting automatic control of the feed mechanism and for varying the range of movement of the punching mechanism comprises an upstanding projection 70 formed integral with the valve operating rod 43 and engageable by a stop plunger 71 mounted in a guide bracket 72, herein formed integral with the rear head block 24 of the hammer motor. The stop plunger 71 is provided with a series of notches 73 with which a positioning pin 74, arranged in a bore in the guide bracket 72, operates in the adjustment of the stop plunger. By removing the pin 74 and sliding the stop plunger into different positions, it is evident that the time of engagement of the projection 70 with the stop plunger may be varied, as desired.

Passages 75 are provided to conduct lubricant carried in the motor exhaust through port 67, to the guideways 10, 10 and guides 12, 12. The guides and guideways may be case hardened to 5 reduce wear.

The operation of the improved punching mechanism will be clearly apparent from the description given. When the drill steel 4 is properly positioned with respect to its clamping mechanism 3 and stop plate 6, the operator grasps the handle 45 to push the operating rod 43 rearwardly, thereby to rotate, through the links 41 and lever 39, the control valve 38 into a position to supply motive fluid through the hammer motor supply passages to the hammer motor cylinder, thereby to effect rapid reciprocation of the hammer piston. At the same time, pressure fluid is supplied from the valve chamber through passage 58 and port 60 to the rear end of the feed cylinder bore, the pressure fluid acting on the rear pressure area of the feed piston 32 to feed the hammering mechanism bodily along the frame guideways 10, 10. Upon engagement of the point of the punch pin 20 with the drill steel, the cylindrical striking block 22 is held temporarily stationary so that upon continued movement of the hammer mechanism with respect thereto this striking block is brought into striking relation with the hammer piston, and as a result, upon continued forward movement of the hammering mechanism the punch pin is driven into the drill steel bore by the repeated blows of the hammer piston against the striking block 22. When the reforming of the drill steel bore is completed, that is, when the punch pin has been driven into the drill steel bore a sufficient distance, the stop plunger 71 engages the projection 70 of the valve control mechanism, thereby to swing the valve from its forward feed position to its reverse feed position, while the supply of motive fluid to the hammer cylinder is continued, and as a result the direction of feed is automatically reversed. Pressure fluid then flows through passages 57, 59 to the forward end of the feed cylinder bore to act on the forward pressure area of the feed piston, and as a result the hammer mechanism is fed rearwardly along the frame guideways. If the punch pin sticks within the steel bore, the striking block 22 will be held stationary while the rearward movement of the hammer mechanism continues, thereby bringing the striking head 29 of the striking block rod or bar 27 into a position wherein the rear end of the hammer piston will percussively actuate the same, thereby driving the punch pin out of the work with a hammering action. When the punch pin is withdrawn from the drill steel bore, the operator may operate the control rod handle 45 to move the control valve into its neutral position, thereby shutting down both the hammer motor and feed.

As a result of this invention, it will be noted that an improved punching mechanism is provided for reforming the bore of a hollow rock drill steel subsequent to the drill sharpening process, wherein the punch pin for opening the steel bore is driven into and out of the bore with a hammering action. It will further be noted that by the provision of the improved variable range control mechanism, it is possible to vary the length of travel of the hammering mechanism and to effect automatic reversal of the direction of feed when the punch pin has been driven into the steel bore a sufficient distance. These and other uses and advantages of the improved punching mechanism

will be clearly apparent to those skilled in the art.

While there is described in this application one form which the invention may assume in practice, it will be understood that this form is shown for purposes of illustration and that the invention may be modified and embodied in various other forms without departing from its spirit or the scope of the appended claims.

What I claim as new and desire to secure by Letters Patent is:

1. In a punching mechanism, a guide, a hammer mechanism mounted on said guide for movement therealong and having reversible hammering means for driving with a hammering action a punch pin into and out of the work, means for feeding said hammer mechanism forwardly and rearwardly along said guide, means for effecting operation of said hammer mechanism during both forward and reverse feeding movements thereof, and mechanically actuated means for automatically reversing the direction of feed when said hammer mechanism has been fed in one direction a predetermined distance including an abutment mounted exteriorly of and movable with said hammer mechanism, and a reversing control element supported against bodily movement with respect to said guide and having operating means engageable and actuated by said abutment.

2. In a punching mechanism, a guide, a reversible punch pin hammer mechanism slideable on said guide and having reversible hammer means for driving the punch pin either forwardly or rearwardly, means for feeding said hammer mechanism forwardly and rearwardly along said guide, means for automatically reversing the direction of feed when said hammer mechanism has been fed in one direction a predetermined distance, and associated means for varying the distance of travel of said hammer mechanism.

3. In a punching mechanism, a support providing a guideway, a hammer mechanism mounted on said guideway for movement therealong and having reversible hammering means for hammering a punch pin into and out of a drill steel bore, reversible means for feeding said hammer mechanism forwardly and rearwardly along said guideway, means for effecting operation of said hammer mechanism during both forward and rearward feeding movements thereof, and mechanically actuated means for automatically reversing said feeding means when said hammer mechanism has driven the punch pin a predetermined distance into the drill steel bore including an abutment mounted exteriorly of and movable with said hammer mechanism, and a reversing control element mounted on said support and engageable and actuated by said abutment.

4. In a punching mechanism, a support having a guideway, a hammer mechanism slideable on said guideway and having reversible hammering means for hammering a punch pin into and out of a drill steel bore, reversible means for feeding said hammer mechanism forwardly and rearwardly along said guideway, means for automatically reversing said feeding means when said hammer mechanism has driven the punch pin a predetermined distance into the drill steel bore, and associated means for varying the distance which the punch pin may be driven into the drill steel bore.

5. In a punching mechanism, a support having a guideway, a hammer mechanism slideable on said guideway for hammering a punch pin into

and out of a drill steel bore, reversible means for feeding said hammer mechanism forwardly and rearwardly along said guideway, means for automatically reversing said feeding means when said hammer mechanism has driven the punch pin a predetermined distance into the drill steel bore, and associated means for varying the distance which the punch pin may be driven into the drill steel bore, said feed reversing means including a control element for effecting feed reversal and said associated means including a control rod guided on said support, a projection on said control rod and an abutment movable with said hammer mechanism and engageable with said control rod projection.

6. In a punching mechanism, a support having a guideway, a hammer mechanism slidable on said guideway and having reversible hammering means for hammering a punch pin into and out of a drill steel bore, reversible means for feeding said hammer mechanism forwardly and rearwardly along said guideway, means for automatically reversing said feeding means when said hammer mechanism has driven the punch pin a predetermined distance into the drill steel bore, and associated means for varying the distance which the punch pin may be driven into the drill steel bore, said feeding means comprising a feed cylinder containing a feed piston, said reversing means including a reversing valve for controlling the supply of actuating fluid to the opposite ends of said feed cylinder, and said associated means including an abutment movable with the hammer mechanism and operative upon a predetermined forward feeding movement of said hammer mechanism to effect reversal of said valve.

7. In a punch mechanism, a support having a guideway, a punch pin hammering mechanism slidably mounted on said guideway for driving a punch pin with a direct hammering action into and out of a drill steel bore, reversible feeding means for said hammering mechanism, control means for effecting feed reversal, and operating means for said control means for effecting automatically feed reversal when the punch pin has been driven into the drill steel bore a predetermined distance including a longitudinal rod slidably guided on said support and operatively connected to said control means, and an abutment rod mounted on said hammering mechanism and engageable with said first mentioned rod.

8. In a punch mechanism, a support having a guideway, a punch pin hammering mechanism slidably mounted on said guideway for driving a punch pin with a direct hammering action into and out of a drill steel bore, reversible feeding means for said hammering mechanism, control means for effecting feed reversal, and operating means for said control means for effecting automatically feed reversal when the punch pin has been driven into the drill steel bore a predetermined distance including a longitudinal rod slidably guided on said support and operatively connected to said control means, an abutment rod mounted on said hammering mechanism and engageable with said first mentioned rod, and means for varying the depth of penetration of the punch pin within the steel bore including adjusting means for said abutment rod, said adjusting means including a series of notches on said abutment rod and a stop pin engageable with said notches to hold said rod in adjusted position, said abutment rod being slideable axially into different

positions to engage said first mentioned rod at different times.

9. In a punching mechanism, a reversible punch pin hammer mechanism having reversible hammering means for percussively actuating the punch pin to drive the latter either forwardly or rearwardly, means for feeding said hammer mechanism forwardly and rearwardly to move the punch pin toward and from the work during the percussive action thereon, means for automatically reversing the direction of feed when said hammer mechanism has been fed toward the work a predetermined distance, and means incorporated in said automatic means for varying the distance of travel of said hammer mechanism toward the work.

10. In a punching mechanism, a hammer mechanism having reversible hammering means for hammering a punch pin into and out of a drill steel bore, reversible means for feeding said hammer mechanism forwardly and rearwardly to move the punch pin toward and from the drill steel during the hammering action thereon, means for effecting operation of said hammer mechanism during forward and rearward feeding movements thereof, and mechanically actuated means for automatically reversing said feeding means when said hammer mechanism has driven the punch pin a predetermined distance into the drill steel bore including an abutment mounted exteriorly of and movable with said hammer mechanism and a movable reverse-effecting control element relative to which said hammer mechanism is bodily movable, said control element engageable and actuated by said movable abutment.

11. In a punching mechanism, a hammer mechanism having reversible hammering means for hammering a punch pin into and out of a drill steel bore, reversible means for feeding said hammer mechanism forwardly and rearwardly to move the punch pin toward and from the drill steel during the hammering action thereon, means for effecting operation of said hammer mechanism during forward and rearward feeding movements thereof, means for automatically reversing said feeding means when said hammer mechanism has driven the punch pin a predetermined distance into the drill steel bore, and means associated with said automatic means for varying the distance which the punch pin may be driven into the drill steel bore.

12. In a punching mechanism, a support providing a guideway, a hammering mechanism mounted on said guideway for movement therealong, reversible means for moving said hammering mechanism forwardly and rearwardly along said guideway, means for automatically reversing said feeding means when said hammering mechanism has moved along said guideway a predetermined distance in one direction, and associated means for varying the distance of movement in said direction including a control element on said support for effecting feed reversal, said hammering mechanism movable bodily relative to said control element, a control rod supported for axial movement on said support, a projection on said control rod, and an adjustable abutment mounted exteriorly of and movable with said hammering mechanism and engageable with said control rod projection for axially moving said control rod.

13. In a punching mechanism, a support providing a guideway, a punch pin, hammering mechanism mounted on said guideway for move-

ment therealong, reversible feeding means for said hammering mechanism for moving the latter forwardly and rearwardly along said guideway, control means for effecting feed reversal, 5 manual operating means for said control means including a longitudinal control rod supported for axial movement on said support and operatively connected to said control means, and automatic operating means for said control means for effecting automatic feed reversal when said hammering mechanism has moved along said guideway in one direction a predetermined distance including said longitudinal control rod, and an abutment rod supported by said hammering 10 mechanism and engageable with said first mentioned rod for axially moving the latter.

14. In a punching mechanism, a support providing a guideway, a punch pin, hammering mechanism mounted on said guideway for movement therealong, reversible feeding means for said hammering mechanism for moving the lat- 15

ter forwardly and rearwardly along said guideway, control means for effecting feed reversal, and operating means for said control means for effecting automatic feed reversal when said hammering mechanism has moved along said guideway in one direction a predetermined distance including a longitudinal control rod supported for axial movement on said support and operatively connected to said control means, an abutment rod supported by said hammering mechanism and engageable with said first mentioned rod for axially moving the latter, and means for varying the depth of penetration of the punch pin within the steel bore including adjusting means for said abutment rod, said adjusting means including a series of notches on said abutment rod and a stop pin engageable with said notches to hold said rod in adjusted position, said abutment rod being movable axially into different positions to engage said first mentioned rod at different times. 20

PAUL H. NAST.
